CLAIM

The ornamental design for a computer monitor assembly with hub stand as shown and described.

DESCRIPTION

FIG. 1 is a front, right, top perspective view of a computer monitor assembly with hub stand showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an exploded front, right, top perspective view, showing the computer monitor assembly with hub stand of FIGS. 1-7 separated;

FIG. 9 is an enlarged detail view of portion "9" of FIG. 1; FIG. 10 is an enlarged detail view of portion "10" of FIG. 1;

FIG. 11 is an enlarged detail view of portion "11" of FIG. 1; FIG. 12 is an enlarged detail view of portion "12" of FIG. 1;

FIG. 13 is an enlarged detail view of portion "13" of FIG. 4;

FIG. 14 is an enlarged detail view of portion "14" of FIG. 5;

FIG. 15 is an enlarged detail view of portion "15" of FIG. 6; and,

FIG. 16 is an enlarged detail view of portion "16" of FIG. 6.

The even-dash broken lines depict portions of the computer monitor assembly with hub stand that form no part of the

(Continued)

claimed design. The dot-dot-dash broken lines indicate the extents of the enlarged detail views and form no part of the claimed design.
